UNITED STATES PATENT OFFICE.

ELISHA F. PARKS, JR., AND PHILIP G. LANG, JR., OF BALTIMORE, MARYLAND.

SHIELD AND ATTACHMENT FOR TRIMMER BELTS.

Application filed January 4, 1922. Serial No. 527,042.

To all whom it may concern:

Be it known that we, ELISHA F. PARKS, Jr., and PHILIP G. LANG, Jr., citizens of the United States, residing, respectively, at 5 Baltimore County and Baltimore city, in the State of Maryland, have invented certain new and useful Improvements in Shields and Attachments for Trimmer Belts; and we do hereby declare the following to be a full, 10 clear, and exact description of the invention, such as will enable others skilled in the art to which it appertains to make and use the same.

Our invention relates to shields and attachments for trimmer belts such as are used in storing cargoes of coal or other materials on board ships, or in placing said materials in bins or other storage receptacles.

Among the objects of our invention are:— 20 To produce a shield which can be readily secured to any approved form of belt.

To produce a shield which can be blanked and shaped readily by means of dies so that the same can be furnished at a reasonable 25 cost.

To produce a shield capable of being used with any approved form of attachment so that the attachment will drive the material that is to be trimmed and the shield will prevent the impact of the material upon the belt 30 from wearing the latter.

To produce a reinforcement for use with our improved shields and attachments so that stresses coming upon one of the shields 35 or attachments will be transmitted throughout the width of the belt, whereby the application of undue stresses to one part of the belt is prevented.

Heretofore, a variety of attachments have 40 been secured to trimmer belts, but the belts where subject to considerable wear due to the impact of the material to be trimmed. This we obviate with our improved shield, and while said shield is primarily intended for use with our improved attachment shown in 45 our co-pending application for U. S. Letters Patent S. N. 409,507, filed September 10, 1920, yet it is capable of use with any form of attachment, or capable of use without any 50 attachment. The re-enforcing element of our improved shield may also be used to reinforce the belt where the attachment is joined thereto.

One form of our shield and reinforcement

is shown in the accompanying drawings, in 55 which:—

Figure 1 is a plan view of a belt equipped with our improved shield, reinforcement and attachment.

Fig. 2 is a view of the parts shown in Fig. 60 1 looking in the direction of the arrow 2 in said figure.

Fig. 3 is a view of the parts shown in Fig. 65 2 looking in the direction of the arrow 3 in said figure.

Fig. 4 is a plan view of one of the re-enforcements.

Figs. 5 and 6 are end views respectively of 70 our improved shield and attachment, the teeth not being bent over.

In the drawings:—

5 is a belt which may be of leather or any 75 approved material, of any suitable width, driven in any approved manner and controlled by any suitable mechanism so that it will be directed against the material that is to be trimmed.

The attachment shown at 6 is illustrated, 80 described and claimed in our co-pending applications for U. S. Letters Patent above noted excepting as regards certain differences to which reference will be hereinafter made.

Each of our improved shields consists of 85 a plate 7 having upon each end a plurality of teeth 8 bent at right angles thereto.

It is to be noted that the teeth 8—8 on the ends of each shield are in staggered relation to each other as illustrated by the teeth 9 and 10 in Fig. 1.

There are similar teeth 11—11 formed in 90 staggered relation upon the ends of the attachment 6, two of which are shown dotted at 12 and 13 in Fig. 1.

The staggered relation between the teeth 95 at the ends of the attachment 6 shown herein is the feature wherein said attachment differs from the attachment shown in our co-pending application for U. S. Letters Patent above noted.

In order to distribute the stress when one of the attachments 6 or the plate 7 is subjected to an undue force, we provide the re-enforcement 14 which consists of a flat plate having a plurality of rectangular holes such as 15, each hole being for the reception of one of the teeth 8 or 11.

In applying the attachment 6 and plate 7

to the belt 5, the re-enforcements 14 are placed upon the teeth 8 and 11 and then said teeth are driven through the belt 5, or passed through holes perforated therein in any approved manner. The ends of the teeth 8 and 11 are then bent over on the inner side of the belt 5 as shown at 16 and 17, respectively.

The re-enforcements 14 also serve to prevent the edges such as 18 of the attachment 6 from cutting into the belt. They also serve to prevent the ends such as 19 of the plate 7 from cutting into the belt.

It is to be noted that by reason of the fact that the teeth 9 and 10 are in staggered relation to each other and that the teeth 12 and 13 are also in staggered relation to each other, and that the teeth 10 and 12 are in staggered relation to each other when an attachment 6 and plate 7 are assembled upon the belt with their edges in line, it follows that the bent over portions 16 and 17 are also in staggered relation to each other.

The parts are so constructed that the bent over portions 16 and 17 are in staggered relation in order to increase the coefficient of friction of the belt with the driving pulley when the bent over portions 16 and 17 are passing around same. It is obvious that if the bent over portion 16 were opposite the bent over portion 17, they would be circumferentially in line upon the pulley and the interstitial belt material would not come into contact with the pulley. By placing the portions 16 and 17 in staggered relation, the belt material is in circumferential alignment with said portions and the coefficient of friction of the belt with the pulley is increased.

The attachment 6 is for the purpose of 40 positively driving the material to be

trimmed. The shields comprising the plate 7 serve to prevent the abrasion of the surface of the belt 5. The re-enforcements 14 distribute stresses from any attachment or shield throughout the width of the belt and thus prevent an undue strain at any one part. The centre of the top of 6 is in contact with the belt to support the ends.

By these means, we provide a trimmer belt capable of performing effective work and having maximum wearing qualities.

While we have shown one form of our improved attachment, shield and re-enforcement, we do not desire to be limited to the exact construction shown in the drawings, 55 for many changes may be made therein without departing from the spirit of our invention.

We claim:—

1. The combination with a belt, and an attachment and a shield mounted end to end on said belt, of teeth projecting from the ends of said attachment and shield through said belt and lying adjacent the underside thereof, the teeth on the abutting ends of 65 said attachment and said shield being in staggered relation with each other and oppositely disposed.

2. The combination with a belt and shields mounted end to end thereon, of teeth projecting from the ends of said shields through said belt and lying adjacent the underside thereof, the teeth on the abutting ends of 70 said shields being in staggered relation with each other oppositely disposed.

In testimony whereof, we affix our signatures.

ELISHA F. PARKS, JR.
PHILIP G. LANG, JR.
